UNITED STATES PATENT OFFICE.

FREDRICK L. TESMER, OF CLEVELAND, OHIO, ASSIGNOR, BY MESNE ASSIGNMENTS, TO THE ASHTABULA BOW SOCKET COMPANY, OF ASHTABULA, OHIO, A CORPORATION OF OHIO.

TOP FOR VEHICLES.

1,246,352.

Specification of Letters Patent. Patented Nov. 13, 1917.

Application filed March 6, 1914, Serial No. 822,847. Renewed April 14, 1917. Serial No. 162,190.

To all whom it may concern:

Be it known that I, FREDRICK L. TESMER, a citizen of the United States, and a resident of Cleveland, county of Cuyahoga, and State 5 of Ohio, have invented a new and useful Improvement in Tops for Vehicles, of which the following is a specification, the principle of the invention being herein explained and the best mode in which I have contemplated 10 applying that principle, so as to distinguish it from other inventions.

The present improvements relate in general to folding tops for vehicles and the like, and in particular to that type of top which 15 is now generally known among the trade as a "one-man" top. The essential feature of the so-called one-man top is the support of the forward portion from the rear bows of the top without providing any direct supports between the forward portion of the top 20 and the vehicle body. Various attempts have been made along these lines, but it is extremely difficult to provide such a construction which will be both rigid and easy 25 to fold, and unless these two qualities are secured the construction presents but few advantages over the usual type of vehicle top.

In the present invention I have provided 30 a top of this type which requires but a few bows and in which the forwardly extending bows supporting the front end of the top are rigidly secured against side play, the bracing means for the same being so connected 35 that they offer little resistance to folding when the extreme forward bow is bent backwardly. To the accomplishment of the foregoing and related ends, said invention, then, consists of the means herein- 40 after fully described and particularly pointed out in the claims.

The annexed drawing and the following description set forth in detail certain mechanism embodying the invention, such dis- 45 closed means constituting, however, but one of the various mechanical forms in which the principle of the invention may be used.

In said annexed drawing:—

Figure 1 is a side elevation of the pre- 50 ferred type of my improved vehicle top; Fig. 2 is a similar view of a modified form of construction; Fig. 3 is a partial plan view of the bows in Fig. 1; and Fig. 4 is a partial plan view of the bows in Fig. 2.

55 It will be understood that the present top

may be used on any desired type of vehicle, such as automobiles, carriages, boats and the like, although it has here been illustrated for convenience as attached to the body of an automobile. The top has but one point 60 of support upon the body of the vehicle, at which point two divergently extending rear bows 1 and 2 are pivotally attached. The forwardly extending one of such bows may be termed the main bow 1 and suitably attached to this bow, intermediate its ends, is a forwardly extending, articulated, auxiliary bow 3, the attachment being preferably a pivotal one. This auxiliary bow 3 is articulated at substantially the center, forming 65 a forward portion 4 and a rear portion 5, the forward portion 4 having attached to it the front end of the cover 6 of the top. It is necessary in this type of tops to provide a bow similar to the present auxiliary 70 bow which will lie substantially horizontal when extended, for the purpose of supporting the forward end of the top when in raised position, and this bow is variously termed in the trade, an outrigger or auxiliary bow. It is necessary, however, to properly brace or support this forwardly 75 extending auxiliary bow in order that the same may not sway too greatly upon movement of the vehicle, and since there are to 80 be no supports from the forward end of the vehicle to the auxiliary bow the bracing must be carried either to the rear portion of the vehicle or to the main or rear bows.

It is desirable, in order to present a neat 85 appearance, to provide a supplemental bow 7 which is mounted upon the rear portion of the articulated auxiliary bow, either pivotally or slidably, and in the present instance I make the connection a pivotal one but provide the inner end of the bow 7 with a sleeve 8 which fits over the rear portion 5 of the auxiliary bow and has a limited movement with respect to the same, such movement being controlled by means of a pin 9 mounted upon the portion 5 and operating in a slot 10 formed in the sleeve 8. This supplemental bow extends upwardly and forwardly, being substantially parallel with the main bow and serves to support the top 105 intermediate the main bow and the forward end of the same, thus giving a graceful curve to the top covering 6. The purpose of the slidable connection between bows 5 and 7 is to permit the use of a longer bow 7 110

thus dividing the space between bows 1 and 4, equally. It is only possible to use this longer bow when the same is slidably connected to the bow 5 since otherwise the bow 7 will not lie parallel to the bow 1 when folded. By the slidable connection the bow 7 is given two positions relative to the bow 5.

In the present construction I brace the forward portion 4 of the auxiliary bow 10 from the upper part of the main bow. In this way the braces are hidden in the upper portion of the top and are not visible from the side of the vehicle. Braces 11 are pivotally attached to the upper portion of the 15 main bow 1 beyond the point of attachment of the rear portion 5 of the auxiliary bow, and these braces are connected in any suitable manner with the forward portion of the auxiliary bow 3. This attachment of 20 the braces 11 to the bow 3 may be either direct, as shown in Fig. 2, or indirect, as shown in Fig. 1, in which construction the outer end of the braces 11 are pivotally attached to other braces or struts 12 which 25 are themselves pivotally attached to the forward portion of the auxiliary bow and to the supplemental bow 7. The struts 12 are pivoted to the portion 4 of the auxiliary bow adjacent to the rear end of the same 30 and are disposed between the sides of the bow 3.

In this way it is possible to support the forward portion 4 of the auxiliary bow 3 from the upper portion of the main bow 1 35 and to hold in proper position the supplemental bow 7 by means of a strut extending from the forward portion of the auxiliary bow. All of the braces are covered by the downwardly extending sides of the top 40 cover.

In order to fold the top it is necessary to first disconnect the same from the wind shield or other portion of the vehicle to which the forward end is usually attached, 45 when the rear portion 5 of the supplemental bow is swung downward until parallel to the main bow in the position shown in dotted outline in Fig. 1. This action carries the forward portion 4 of the auxiliary 50 bow alongside the rear portion and parallel with the same, and forces the supplemental bow 7 into a similar position parallel with a part of the rear portion 5 of the auxiliary bow and parallel with the upper part of 55 the main bow. The brace 11 is swung forward into a similar parallel position, while the strut 12 which causes the movement of the supplemental bow is also to be found parallel with the latter when the top is 60 thus folded. It is not necessary to manipulate any of the braces or to prepare any of the same for movement, it being sufficient to detach the forward end of the top from the wind shield or other supports and to 65 swing the rear portion of the auxiliary bow

downward into a position parallel with the main bow. There are no stop hinges in any of the braces or bows which must be broken before the top can be folded, nor are there any movements necessary except a single 70 swinging down of the bow already referred to, this movement causing the positioning of all of the bows and braces parallel with the main bow.

The ease with which the present top may 75 be folded constitutes one of its more important advantages, the others being its rigidity when extended and the simplicity of the construction. An additional advantage is the neat appearance of the top when 80 raised, there being no braces, rods or the like visible from the side of the vehicle.

Other modes of applying the principle of my invention may be employed instead of the one explained, change being made as regards the mechanism herein disclosed, provided the means stated by any of the following claims or the equivalent of such 85 stated means be employed.

I therefore particularly point out and 90 distinctly claim as my invention:

1. In a vehicle top, the combination of a main bow, an articulated auxiliary bow pivotally connected to said main bow, a supplemental bow pivotally and slidably attached 95 to the rear portion of said auxiliary bow, struts pivotally attached to the forward portion of said auxiliary bow and connected to said supplemental bow to support the latter, and braces pivotally attached to said main bow and connected to said struts, thereby supporting the outer portion of said auxiliary bow.

2. In a vehicle top, the combination of a main bow, an articulated auxiliary bow pivotally connected to said main bow, a supplemental bow pivotally and slidably attached to the rear portion of said auxiliary bow, struts pivotally attached to the forward portion of said auxiliary bow and being 105 similarly connected to the supplemental bow to support the latter, and braces pivotally attached to said main bow and being also pivotally connected to said struts adjacent to the point of attachment of the latter to the forward portion of said auxiliary bow, thereby supporting the latter.

3. In a vehicle top, the combination of a main bow, an articulated auxiliary bow pivotally connected to said main bow, a supplemental bow pivotally and slidably attached to the rear portion of said auxiliary bow, struts pivotally attached to said main bow and connected to the forward portion of 120 said auxiliary bow, and bracing means pivotally attached to said supplemental bow and operating against said struts to support said supplemental bow.

4. In a vehicle top, the combination of a main bow; an articulated auxiliary bow piv- 125

otally connected to said main bow; links connecting said main bow with the forward portion of said auxiliary bow; and a supplemental bow shiftably attached to the 5 rear portion of said auxiliary bow and operatively connected with the forward portion of the latter, so as to be folded and unfolded in unison therewith.

5. In a vehicle top, the combination of a 10 main bow; an articulated auxiliary bow pivotally connected to said main bow; links connecting said main bow with the forward portion of said auxiliary bow; and a supplemental bow slidably attached to the rear 15 portion of said auxiliary bow and operatively connected with the forward portion of the latter, so as to be folded and unfolded in unison therewith.

6. In a vehicle top, the combination with 20 a main bow, an articulated auxiliary bow pivotally connected to said main bow, links pivotally attached to said main bow and connected to the forward portion of said auxiliary bow, a supplemental bow pivotally 25 and slidably attached to the rear portion of said auxiliary bow, and bracing means pivotally attached to said supplemental bow and operating against said links to support said supplemental bow.

30 7. In a vehicle top, the combination of a main bow, an articulated auxiliary bow piv-

otally connected to said main bow, a supplemental bow pivotally and slidably attached to the rear portion of said auxiliary bow, links pivotally attached to the forward portion of said auxiliary bow and connected to said supplemental bow to support the latter, and other links pivotally attached to said main bow and connected to said first-named links, thereby supporting 40 the outer portion of said auxiliary bow.

8. In a vehicle top, the combination of a main bow, an articulated auxiliary bow pivotally connected to said main bow, a supplemental bow pivotally and slidably attached 45 to the rear portion of said auxiliary bow, links pivotally attached to the forward portion of said auxiliary bow and being similarly connected to the supplemental bow to support the latter, and other links pivotally attached to said main bow and being also pivotally connected to said first-named links adjacent to the point of attachment of the latter to the forward portion of said auxiliary bow, thereby supporting the latter. 50 55

Signed by me, this 3rd day of March, 1914.

FREDRICK L. TESMER.
